A. V. LIPINSKI.

METHOD AND APPARATUS FOR CARRYING OUT CHEMICAL REACTIONS BY MEANS OF
MAGNETICALLY SPREAD OUT ELECTRIC ARCS.

APPLICATION FILED MAR. 6, 1918.

1,281,604.

Patented Oct. 15, 1918.

UNITED STATES PATENT OFFICE.

ANTON V. LIPINSKI, OF ZURICH, SWITZERLAND.

METHOD AND APPARATUS FOR CARRYING OUT CHEMICAL REACTIONS BY MEANS OF MAGNETICALLY-SPREAD-OUT ELECTRIC ARCS.

1,281,604.

Specification of Letters Patent. Patented Oct. 15, 1918.

Application filed March 6, 1918. Serial No. 220,830.

To all whom it may concern:

Be it known that I, ANTON VICTOR LIPINSKI, a citizen of the Republic of Switzerland, residing at Carmenstrasse 51, Zurich, Switzerland, have invented certain new and useful Improvements in Methods and Apparatus for Carrying Out Chemical Reactions by Means of Magnetically-Spread-Out Electric Arcs; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

In my earlier application, (Ser. No. 84426 of March 15, 1917) I have described a method for carrying out chemical reactions by means of magnetically spread out electric arcs, according to which flowing masses of gas are caused to act upon both sides of the electric flames, whereby at least one of said gas currents operates as a gas wall support for the flames against which support the flames are flattened by the other current of gas.

In carrying out said method, it has been found, that the quantity of energy required for maintaining the flame between the electrodes over their whole active length is not always available or that it is subjected to variations. When the energy decreases for instance in such a manner, that it sinks below the value required for the maintenance of the whole flame structure, the arc stops always at the same point of the electrodes, so that the latter are burnt out and the furnace is then no longer in working order. Thus, it would be necessary to stop the working of the furnace as soon as the whole energy required for the feeding of the furnace is no longer supplied to the electric distributing network, which would be the case, for instance, when the plant is momentarily subjected to a maximum load or the like.

When the electrodes are arranged in such a manner that the points of said electrodes at which the arc is produced, are at an equal distance, it has now been found, by experiments, that the variations of the energy can be entirely neglected by imparting to at least one of the two gas currents operating as a gas wall support, both a movement in

the direction of the shortest path between neighboring electrodes and also a revolving movement about the axis of the produced flame sheet.

This invention will now be more particularly described with reference to the accompanying drawing illustrating by way of examples two embodiments of apparatuses for carrying out the improved method.

In this drawing:

Figure 1 is a vertical longitudinal cross-section through the first embodiment;

Fig. 2 is an enlarged cross-section on the line 2-2 of Fig. 1.

Fig. 2^a is an enlarged detail perspective view.

Fig. 3 is a vertical longitudinal cross-section through the second embodiment and

Fig. 4 is a plan view of a detail of this embodiment.

Referring to Fig. 1, it will be seen, that during normal working a horizontal flame disk is struck between the two parallel ring electrodes 1 and 2, arranged within a reaction chamber of the furnace, said flame being produced owing to a magnetic action upon the electric arcs. The inner ends of the two inlet pipes 6 and 7, one of which is concentrically disposed within the other, confine near the inner electrode 2 an annular gap 4 through which issues one of the gas currents, while an inlet pipe 5 supplies the second current of gas to the opposite side of the inner electrode 2. The two gas currents act on both sides over the entire surface of the flame disk or sheet constituting the flame, whereby one of said currents operates as a gas wall support for the flame, against which support said flame is flattened by the other current of gas.

Between the walls of the inner pipe 6 and outer pipe 7 are disposed a plurality of blades 8 (see also Fig. 2). The reaction gases flow through the inner pipe 6 and then through passages provided on both sides of the electrode 2 between the latter and the annular gaps 4 and 10 respectively. The blades 8 impart to the cooling gases issuing through the annular gap 4—although said gases are already blown at a high velocity along the plane of the electrodes—not only a movement in the direction of the shortest path between the two electrodes 1 and 2, i. e., in a radial direction, but also a revolving movement about the vertical axis of the

flame sheet produced between the electrodes 1 and 2. Thus, the issuing cooling gases do not only flow in a radial direction over the arcs, but also in a tangential direction.

5 Each time, that the whole energy is no longer available, owing to variations of the energy supplied, only a part of the ring disk, and not the whole space between the electrodes 1 and 2, will be filled out by a flame 10 disk or sheet. In the kind of furnaces described in the application above referred to, it has been found, that in such a case the disk-shaped flame stops always at the same point of the electrodes. Thus, the latter is 15 liable to be overheated, so that they may be worn out too soon, or they may even fuse causing an interruption in the working of the furnace.

In consequence of the fact, that a tangential component of motion is imparted to the 20 current of gas issuing through the annular gap 4, the flame disk does not stop at the same spot or point between the two electrodes, but circulates or rotates. Thus, the 25 electrodes are preserved and a burning out of them and an interruption of the working of the furnace is even prevented in those cases where the whole energy is not supplied for a longer period of time. Moreover, said 30 revolving movement of the gas current has the effect to still more flatten and spread out the flame disk, so that the quantity of gas available for the reaction is increased.

In the embodiment shown in Figs. 3 and 35 4 comprising three electrodes 13, 14, 14¹, the reaction gases flow through the apertures 12 out of the heart-shaped chamber 11 and come within reach of the electric flame mantles which are struck between the rod-shaped electrode 13 and the ring electrode 14¹ and the latter and the ring electrode 14. The chilling gases issue through an annular nozzle 15 surrounding the rod-shaped electrode 13. The magnetic field which exerts a 45 spreading-out action upon the electric arcs is indicated by the arrows 16. In the annular channel 17 leading to the annular nozzle 15 are arranged a plurality of curved, helical-shaped blades 18 (see also Fig. 4), 50 which prevent the gases issuing through the annular nozzle 15 from flowing along the shortest path over the conical electric flame mantle to the ring electrode 14. Also in this embodiment, the blades 18 impart to 55 said gases an additional revolving movement about the vertical axis of the electric flame mantle, said axis passing through the centers of the electrodes 14, 14¹ and coinciding with the longitudinal axis of the rod-shaped electrode 13. Thus, the gases will 60 follow approximately along a path which is

shown in Fig. 3 by the point and dash line 19. Further, the gases exert also in this embodiment a spreading-out action upon the electric flame mantle and in the case the 65 whole quantity of energy is not available, only a part of the electric flame mantle will be produced, this part of the flame mantle is caused to circulate, which results in the same advantages as in the first described embodiment. 70

It will be seen, that the furnaces described are wholly independent of the variations of load occurring in the electrical supply network and that any interruption in the working of the furnaces, due for instance to a burning out of the electrodes, is eliminated. 75

The main idea of the present invention can be applied to all kinds of furnaces illustrated in my earlier application referred to. 80

What I claim now as my invention is:

1. The method, which comprises producing a dispersed arc between electrodes, the points of two coöperating electrodes at which the arc is produced being arranged at an 85 equal distance from each other, thereby maintaining a flame sheet between the electrodes, supplying a gas current to each side of the spread flame over its entire surface and imparting to one of said gas currents, 90 operating as a gas wall support, both a movement in the direction of the shortest path between two neighboring electrodes and a revolving movement about the axis of the produced flame sheet. 95

2. An electric furnace, comprising a furnace having a reaction chamber therein, electrodes so arranged in said chamber that the points of two coöperating electrodes at which the arc is produced are at an equal 100 distance from each other, means to spread the arc to form a sheet bounded by said electrodes, means to supply gases into said chamber and blades arranged in said gas supplying means adapted to impart a revolving movement to the gas issuing from said means. 105

3. An electric furnace, comprising a furnace having a reaction chamber therein, electrodes so arranged in said chamber that the points of two coöperating electrodes at which the arc is produced are at an equal distance from each other, means to spread the arc to form a sheet bounded by said electrodes, means to supply gases into said chamber and curved blades arranged near the outlet 110 of said gas supplying means and adapted to impart a revolving movement to the gas issuing from said means. 115

In testimony that I claim the foregoing as 120 my invention, I have signed my name.

A. V. LIPINSKI.
